(57) **CLAIM**

The ornamental design for a cooler for wine bottles, as shown.

DESCRIPTION

FIG. 1 is a perspective view of a cooler for wine bottles showing my new design;

FIG. 2 is a front elevational view thereof;

FIG. 3 is a rear elevational view thereof;

FIG. 4 is a left side elevational view thereof, the right side being a mirror image.

FIG. 5 is a top plan view thereof;

FIG. 6 is a perspective view of a cooler for wine bottles showing my new design with the door open; and,

FIG. 7 is a front elevational view of FIG. 6.
